Attorney.

UNITED STATES PATENT OFFICE.

WILLIAM S. ARNOLD, OF CLYDE, KANSAS.

RAILROAD-SWITCH.

SPECIFICATION forming part of Letters Patent No. 380,972, dated April 10, 1888.

Application filed November 12, 1887. Serial No. 255,016. (No model.)

To all whom it may concern:

Be it known that I, WILLIAM S. ARNOLD, a citizen of the United States of America, residing at Clyde, in the county of Cloud and State 5 of Kansas, have invented certain new and useful Improvements in Railroad-Switches; and I do hereby declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 My invention relates to an improvement in railway-switches; and it consists in the novel construction and arrangement of the parts thereof, which will be more fully hereinafter described and pointed out in the claims.

20 The object of my invention is to provide a self-throwing switch which averts accident by allowing the same to remain open, as is ordinarily the case, the said switch being operated by a simple and automatically-working construction.

25 In the accompanying drawings, wherein like letters of reference indicate similar parts in the several views, Figure 1 represents a top plan view of my improved construction. Fig. 30 2 is a transverse vertical section on the line *x*-*x* of Fig. 1. Fig. 3 is a longitudinal vertical section on the line *y*-*y* of Fig. 1.

A indicates the main track, and B the side track, which are mounted in the well-known 35 manner. To the under side of one section of the main-track rail A, adjacent to the switching-point, a transversely-arranged metallic bar, C, is secured, which has two rods, *c*, attached to the under side thereof, and are secured to one arm of bell-crank levers D, pivotally supported on suitable fulcrum-pins, *d*, and one end of the bar C is connected to a target, W, by a rod, W'. The central top portion of the bar C has a plate, C', secured there- 40 to, one edge of which is formed with two curved indentations, *c'*, which are alternately engaged by a frictional roller, *e*, carried in the end of a longitudinally-sliding frame, E, which is provided with a rod, E', encircled by a coiled 45 spring, S, the said spring having bearing against an upwardly-projecting lug, *e'*, secured adjacent thereto, and through which and a staple,

*e*², secured to one of the ties, the rod E' has movement. The rear portion of the frame E is reduced and engaged by headed guide-pins 55 *e*³, secured to a transversely-mounted bar, W', upon which the ends of the rails move, and to which the target W is secured to one side of the main track A. The other arm of the bell-crank lever D has a longitudinally-mounted connecting-rod, D', secured thereto, the opposite end of said rod being connected to a transversely-mounted lever, F, passing through a guide-lug, *f*, secured to one side of the rails. The inner end of the lever F is of a curved con- 65 figuration and normally projects upward.

Two curved rails, S' and S², are secured to the ties between the side and main track rails, and project over and are in engagement with the inner curved ends of the levers F, which are 70 mounted on each side of the tracks, having similarly situated connecting-rods and bell-crank levers in connection with the rod *e* of the bar C.

The rails S' and S² project slightly above 75 the rails adjacent to which they are mounted, and the rail S' lies nearer one of the side-track rails, and the oppositely-situated rail S² close to one of the main-track rails. The said rails are enlarged at their upwardly-curved portions to resist the frictional wear of the car-wheels passing thereover. The connecting-rods D' and parts attached thereto are 80 enclosed in sheathing-boxes W², and the rods *c* extend downward on an incline from each side 85 of the under central part of the bar C, and are secured to the bell-crank levers D, as hereinbefore set forth.

When a train runs out on the side track, B, toward the main track, either backward or forward, the first series of car-wheels ride over the rail S' and press said rail and the upwardly-projecting end of the lever F downward, drawing the main track A, to which the bar C is connected, over in alignment with the 90 side track, and at the same time throwing the target W to one side. If the train just leaving the siding would take the direction of travel indicated by the arrow 2, the switch might be left open. The forward wheels of a 95 train, therefore, running on the main track in the direction of the arrow 1 would pass over the rail S' and reverse the movement of the switch and render the main line intact. This 100

is due to the action of the bell-crank levers D and their connections, which operate as will be readily understood.

When the switch is adjusted as just described, 5 the friction-roller e travels from one indentation c' to the other in the edge of the plate C', and a temporary retention thereby obtained.

It will be readily observed that a train moving in the direction of arrow 3 on the main line 10 will only tend to keep the main line intact, as the wheels of the cars would pass over the rail-plate S², which always has the tendency to close the switch.

The utility and advantage of my improved 15 switch and the safety accorded by the use thereof are obviously apparent, and it is unnecessary to further enlarge upon the same herein.

Having thus described my invention, what I claim as new is—

20 1. The combination of the main and side tracks, A and B, the transverse bar C, having the plate C', provided with curved indentations, the roller e, carried by a sliding frame, E, the rods c, the bell-crank levers D, the con-

necting-rods D', the levers F, having inner 25 upwardly-bent ends, and the rails S' and S², substantially as described.

2. The combination of the main and side tracks, A and B, the transverse bar C, having the central top plate, C', provided with curved 30 indentations, the roller e, carried in the end of a spring-actuated sliding frame, E, the rod c, connected to the end of the bar C, the rod W², connected to the bar C and target W, the bell-crank levers D, also connected to the rods c, 35 the connecting-rods D', the levers F, having the inner upwardly-bent curved ends, and the flat upwardly-curved rails S' and S², enlarged at their central portions and adapted to engage with upwardly-projecting ends f of the 40 levers F, substantially as described.

In testimony whereof I affix my signature in presence of two witnesses.

WILLIAM S. ARNOLD.
